UNITED STATES PATENT OFFICE.

WILLIAM L. TAYLOR, OF ROANOKE, VIRGINIA.

GARAGE DOOR.

Application filed May 8, 1924. Serial No. 711,935.

To all whom it may concern:

Be it known that I, WILLIAM L. TAYLOR, a citizen of the United States of America, and resident of Roanoke, in the county of Roanoke and State of Virginia, have invented certain new and useful Improvements in Garage Doors, of which the following is a specification.

This invention relates to doors for garages and the like, and has for an object the provision of a garage and door which will occupy comparatively little space, the said door being capable of opening vertically or practically so, and when the door is open it occupies space above the garage and does not require space at the side of the door opening for its storage.

By reason of the construction of the door and its mounting, there is no liability of damage to the door or its working parts due to collision, and owing to the fact that a counterbalance weight is associated with the mechanism, the door may be readily manipulated to open or close it without employing undue force.

It is a further object of this invention to produce a garage portable in its nature, the sections of which may be readily assembled or dismantled; and furthermore, an object resides in producing a door opening which may be the entire width of the structure, since the door moves vertically and does not require any storage space at either side of the door opening.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in elevation of a garage showing a door in its open position in dotted lines;

Figure 2 illustrates a front view of the said garage;

Figure 3 illustrates a view in elevation showing the joint and hinge between the door and roof structure;

Figure 4 illustrates a sectional view on the line 4—4 of Fig. 3;

Figure 5 illustrates a view of a fragment of the garage showing the hinge between the sections of the door;

Figure 6 illustrates an end elevation thereof;

Figure 7 illustrates a sectional view on the line 7—7 of Fig. 1;

Figure 8 illustrates a sectional view on the line 8—8 of Fig. 1; and

Figure 9 illustrates a sectional view on the line 9—9 of Fig. 1.

In these drawings, 10 denotes the curved roof which extends from the foundation plane on one end to the foundation plane at the other end. The roof is preferably constructed of galvanized iron and it has a door opening closed by a sectional door comprising, in the present embodiment of the invention, the lower section 11 and the upper section 12, each of said sections having angle irons 13 and 14, respectively, secured on their outer surfaces at their meeting edges. Ribs 15 and 16, preferably of angle iron, are also secured to the sections 11 and 12, respectively, and they overlap each other at the joint between the sections. A pintle 17 extends through the overlapped ends of the ribs in order that one section may swing with relation to the other section as the door is being opened or closed.

In the present embodiment of the invention, it is the purpose of the inventor that the section 12 shall be raised at its lower end so that it may be caused to swing upwardly to a substantially vertical position, as shown in dotted lines in Fig. 1, in which position the lower section will fold with relation to the upper section and hang in an approximately vertical position. When the position of parts just described has been assumed, the door opening will be wholly unobstructed and vehicles such as automobiles may enter or leave the garage without hindrance.

The section 12 is hinged to the roof 10 through the employment of a pipe hinge 18 which includes a rod 19 extending beyond the sides of the garage structure. The protruding ends of the rod constitute fulcrums such as 20, on which the levers 21 and 22 are oscillatably mounted in order that the door

sections may be lifted, as will presently appear. The section 12 of the door is provided with a bracket such as 23 at each end and a lever is secured to each bracket so that when 5 the levers oscillate, they raise or lower the door sections. A counterbalance weight 24 is adjustably secured on the end of each lever remote from the end connected to the door and the weight may be adjusted to a 10 position on the lever to cause it to approximately counterbalance the weight of the door. Of course, the door should be slightly heavier than the lever, since the door should remain closed by gravity but capable of being 15 opened by slight force to be exerted in opening or closing the door.

Suitable side sheathing 25, preferably of galvanized iron, forms the enclosure at the sides, and the sections of sheathing may 20 have appropriately stiffened seams to increase the rigidity and durability of the structure.

Angle irons 26 are provided between the roof and the side, and angle sills 27 may be 25 provided to rest on a foundation or the ground line in order that the side sheathing 25 may be attached to it by fastenings 28, such as bolts, rivets or the like.

Where the door opening is formed, the 30 side sheathing may be secured between superimposed angle irons 29 and 30, and the roof section may be secured to the outer surface of the upper or outer angle iron by fastenings 31 such as rivets or the like.

35 The construction of the sills and the joints between the sides and sills may be changed to suit particular requirements, but the con-

struction described is the preferred form as developed.

I claim:

1. A garage structure having a curved roof including a curved roof door, the said roof and door extending in an arc from base to base of the structure, a hinge extending transversely of the roof, a curved door section having its upper end pivoted on the hinge, a pivot connecting the lower edge of the upper door section to the upper edge of the lower door section, weighted arms pivoted between their ends in line with the hinge of the upper door section and pivotally connected to the hinge between the said door sections, and a counterweight on the end of each arm remote from their connection to the hinges of the door sections. 40 45 50 55

2. A garage structure having a curved roof including a curved roof door, the said roof and door extending in an arc from base to base of the structure, a hinge extending transversely of the roof, a curved door section having its upper end pivoted on the hinge, a pivot connecting the lower edge of the upper door section to the upper edge of the lower door section, weighted arms pivoted between their ends in line with the hinge of the upper door section and pivotally connected to the hinge between the said door sections, a counterweight on the end of each arm remote from their connection to the hinges of the door sections, and means 60 65 70 75 for protecting the joints between the door sections and between the uppermost door section and the roof of the structure. 80

WILLIAM L. TAYLOR.
